US00D377485S

United States Patent

[19]

Kaneko et al.**Patent Number: Des. 377,485****Date of Patent: **Jan. 21, 1997**[54] **POINTING DEVICE**

[75] Inventors: **Steven T. Kaneko; Aditha M. Adams; Christopher Alviar, all of Seattle; Ferdinand van Engelen, Bellevue; Dana Kim, Redmond; Bridget C. Greenberg; Dick C. K. Liu, both of Bellevue, all of Wash.**

[73] Assignee: **Microsoft Corporation, Redmond, Wash.**

[**] Term: **14 Years**

[21] Appl. No.: **37,711**

[22] Filed: **Apr. 12, 1995**

[52] U.S. Cl. **D14/114**
